US0D1071787S

(12) **United States Design Patent** (10) Patent No.: **US D1,071,787 S**
(45) Date of Patent: ** Apr. 22, 2025

(54) **CRYSTAL ORNAMENT**

(71) Applicant: **Ting Liu**, Jieyang (CN)

(72) Inventor: **Ting Liu**, Jieyang (CN)

(**) Term: **15 Years**

(21) Appl. No.: **29/976,664**

(22) Filed: **Dec. 3, 2024**

(51) LOC (15) Cl. **11-02**

(52) U.S. Cl.

USPC **D11/131**; D11/121; D11/184
